Term of patent 3½ years

To all whom it may concern:

Be it known that I, Robert B. Karoff, a citizen of the United States of America, and a resident of the city, county, and State of New York, have invented a new, original, and ornamental Design for a Combination Container for Bath Salts and Bath Cologne, of which the following is a specification, reference being had to the accompanying drawing forming a part thereof.

Figure 1 is a perspective view of a combination container for bath salts and bath cologne.

Figure 2 is a top plan view of Figure 1.

My design as shown comprises a pail with a bottle surrounded by pieces of bath salts simulating the appearance of ice, the said bath salts being enclosed in a transparent wrapper, a depression in the wrapper being provided whereby the latter surrounds the bottle.

I claim:
